UNITED STATES PATENT OFFICE.

DONALD MCKAY MACLEOD, OF LOS ANGELES, CALIFORNIA.

WATER-HEATER.

No. 898,123.

Specification of Letters Patent.

Patented Sept. 8, 1908.

Application filed August 27, 1907. Serial No. 390,325.

To all whom it may concern:

Be it known that I, DONALD MCKAY MACLEOD, a citizen of Canada, residing at Los Angeles, in the county of Los Angeles and State of California, have invented a new and useful Water-Heater, of which the following is a specification.

This invention relates to water heaters of that general class in which the flame from a gas burner constitutes the heating medium.

The object of the invention is to provide a water heater in which danger of asphyxiation, due to the escape of gas at the burner tip, should the turning plug be accidentally left open, is positively eliminated.

A further object is to provide a water heater having air conducting pipes extending from the opposite ends of the heater to the atmosphere so as to maintain a continuous current of air through the heater and thus carry off the gas escaping at the burner tip.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a longitudinal sectional view partly in elevation of a water heater constructed in accordance with my invention. Fig. 2 is a transverse sectional view taken on the line 2—2 of Fig. 1. Fig. 3 is a similar view taken on the line 3—3 of Fig. 1.

Similar numerals of reference indicate corresponding parts in all of the figures of the drawings.

The improved heater forming the subject matter of the present invention comprises a sectional casing including a base 5, a top section 6 and an intermediate section 7. The base 5 is secured to a wall or other suitable support by means of brackets 8 and is provided with an annular flange 9 which bears against the intermediate sections 7, there being a similar flange 10 formed on the upper section 6 and over-lapping the intermediate section, as shown. Arranged within the casing at the intermediate section 7 is a hollow disk 11 having a centrally disposed opening

12 formed therein, said disk providing an interior water receiving compartment 13. The chamber or compartment 13 is provided with a transverse partition 14 and communicating with said compartment on one side of the partition is an inlet pipe 15 provided with a cock or valve 16 for controlling the flow of water to said compartment.

Communicating with the water receiving compartment 13 on the opposite side of the partition 14 is one end of a pipe 17 the intermediate portion of which is coiled to form a plurality of convolutions 18 preferably disposed beneath the disk 11 and supported within the casing by clips or similar fastening devices 19. The free end of the coil 18 projects through the intermediate section 7 of the casing and extends to a faucet or other suitable source of discharge. The upper face of the disk 11 is preferably covered with a layer of asbestos 20 having an opening formed therein and disposed in alignment with the opening 12 so as to permit free circulation of air within the casing. Supported on the base 5 is a sectional burner 21 of any approved construction and communicating with one section of the burner is a gas supply pipe 22 provided with a controlling valve 23.

The base 5 is provided with an opening arranged concentric with the burner, and secured to the base 5 at said opening is an air supply pipe 23' which extends through the wall or ceiling of the building and communicates with the atmosphere. Arranged within the opening in the base 5 is a plate or deflector 24 provided with a plurality of radiating lugs 25 which bear against the adjacent walls of the burner and between which the air is forced upwardly and equally distributed to all sides of the burner. The upper section 6 of the casing is provided with a reduced extension 26 and engaging said extension is a discharge pipe or vent 27 which also extends through the wall or ceiling to the atmosphere. It will thus be seen that by means of the pipes 23' and 27 a continuous circulation of air is maintained within the casing so that should the gas be accidentally left turned on the gas escaping at the burner tip will be taken up by the current of air entering through the pipe 23' and carried off through the pipe 27 thus preventing the gas from entering the room and asphyxiating the occupants of the building.

The water heaters may be made in different sizes and shapes and the heating coils

may be disposed above or below the hollow disk as desired.

While the arrangement for removing the escaping gas from the room is principally designed for use in connection with hot water heaters it is obvious that the same may be used with equally good results on gas stoves used for cooking or heating purposes or wherever a device of this character is found desirable.

Having thus described the invention what is claimed is:

1. A water heater for buildings including a casing communicating with the external air only and comprising upper and lower sections and an intermediate section, said lower section being formed with an opening and having an annular flange for engagement with the exterior walls of the intermediate section, a hollow disk secured to the intermediate section and providing an interior water chamber, a partition extending transversely across said chamber, an inlet pipe communicating with the water chamber on one side of the partition, a heating coil arranged beneath the disk and having one end thereof communicating with the water chamber on the opposite side of the partition and its other end extended through the casing, a gas burner disposed within and surrounding the opening in the lower section of said casing, an air supply pipe disposed at said opening, a plate arranged within said opening at the bottom of the casing for deflecting the air laterally in engagement with the burner, and an air vent forming a source of communica-

tion between the upper section of the casing and the atmosphere.

2. A water heater for buildings including a casing communicating with the external air only and having a flat base and provided with a vertically disposed flange, said base being formed with a centrally disposed opening, a hollow disk disposed within the casing and having an opening formed therein and disposed in alignment with the opening in the base, said disk providing an interior water receiving chamber and having a partition extending transversely across the same, an inlet pipe communicating with the water chamber on one side of the partition, a heating coil disposed beneath the disk and having one end thereof communicating with the water chamber on the opposite side of the partition and its opposite end extended laterally through the casing, a sheet of asbestos secured to the upper surface of the disk and provided with an opening disposed in alignment with the opening in the disk, a burner disposed within the casing and arranged concentric with the opening in the latter, an air supply pipe secured to the base at said opening, a vent pipe engaging the flange of the casing, and brackets secured to the base for attaching the casing to a support.

In testimony that I claim the foregoing as my own, I have hereto affixed my signature in the presence of two witnesses.

DONALD MCKAY MACLEOD.
